FLATIRON REST FOR IRONING BOARDS

Cora A. Steen, Inglewood, Calif.

Application November 10, 1951, Serial No. 255,793

4 Claims. (Cl. 248—117.6)

1

This invention relates to flat iron rests or supports, and more particularly to a flat iron rest which is capable of supporting the iron at various locations along the working surface of the ironing board.

It is the primary object of the invention to provide a flat iron rest which may be firmly secured to any ironing board in a desired position, yet which is capable of being extended to support the flat iron at various locations on the working surface of the board, thus making the flat iron easily accessible to the worker.

The invention, together with other objects attending its production, will be more clearly understood when the following description is read in connection with the accompanying drawings, in which:

Fig. 1 is a side elevation of a flat iron rest embodying my invention, the rest being shown secured to one end of a conventional ironing board;

Fig. 2 is a plan view of the same rest;

Fig. 3 is a rear end view of the rest, the board and clamping mechanism being shown fragmentarily;

Fig. 4 is a sectional view taken along the line 4—4 of Fig. 2; and

Fig. 5 is a fragmentary view of one end of a telescoping member which constitutes a part of the invention, and shows details of construction.

The illustrated embodiment of the invention includes a base 10, rigidly attached laterally aligned C-clamps 11 and 12, and a rigidly attached elongated hollow slideway 13. It also includes elongated telescoping members 14, 15, and 16, and a flat iron supporting tray 17.

The base is simply a rigid frame, which in the instant embodiment, includes spaced parallel side plates 18 and 19, an elongated rigid central channel 20 having laterally disposed bracing flanges 21 and 22, the outer edges of which are welded to the side plates 18 and 19. A cross brace rod 23 passes through both side plates 18 and 19, and through the channel 20, and is rigidly secured to all three by welding.

The slideway 13 is supported longitudinally on the web of channel 20, and is welded thereto. In its upper surface the slideway is provided with an elongated slot 24 which is abruptly narrowed near the open end of the slideway to form shoulders, as indicated at 25.

The outermost one of the telescoping tubes 14 is of a diameter to slidably fit the interior bore of slideway 13. At its inner end, tube 14 is closed by an upstanding stop pin 26 of the type clearly shown in Fig. 5. The pin is of a width to fit snugly but slidably within slot 24 in the slideway 13, and thus serves to prevent relative rotation of member 14 within slideway 13. By contact with

2

the closed end 27 of slot 24, and with shoulders 25, the pin 26 also serves to limit the longitudinal movement of member 14 in both directions. The upper end of pin 26 is preferably arcuate, and extends upward only the thickness of the wall of slideway 13. The arc is also concentric with the outer surface of slideway 13, as clearly shown in Fig. 4.

A similar slot and stop pin arrangement is provided for the other telescoping members. Tube 14, for instance, is provided with a longitudinal slot 28 which has shoulders 29. The inner end of tube 15 is closed by stop pin 30. The arcuate upper surface of stop pin 30 slidably fits the interior of slideway 13, so that shoulders 25 do not interfere in any way with the travel of member 15. Contact of pin 30 with pin 26 limits the inward travel of member 15, while contact of pin 30 with shoulders 29 limits the relative outward movement. Sliding contact of the sides of stop pin 30 against the sides of slot 28 prevent relative rotation of the member 15 within member 14.

Similarly member 15 has a slot 31, shoulders 32, and the inner end of member 16 is provided with a stop pin 33 which slidably fits slot 31 and prevents rotation of member 16 in member 15. The upper surface of pin 33 is likewise arcuate and slidably fits the inner surface of member 14, so that neither the narrow portions of slots 24 and 28, nor the shoulders 25 and 29 interfere with the longitudinal movement of member 16. The inward movement of this member is limited by contact of stop pin 33 with pin 30, while the outward movement is limited by contact of pin 33 with shoulders 32, as shown in Fig. 2. It should be noted that the innermost one of the telescoping members 16 is preferably a solid rod and has an upstanding longitudinally disposed guide rib 34 on its upper surface. The width of this rib is such as to permit it to pass snugly through the narrow portions of slots 24, 28, and 31.

The flat iron supporting tray 17 is rigidly secured, as by welding, on the outer end of rib 34. The tray has upstanding integral peripheral flanges 35, 36, 37, 38 and 39, and affixed rigidly to its inner surface it carries two runners or skids 40 and 41, which parallel the telescoping member 16. These skids are spaced apart sufficiently to clear the clamps 11 and 12 when all parts are in their retracted positions, as clearly shown in Fig. 3.

In use the extensible rest is simply positioned on an end of an ironing board 42 and the parallel C-clamps 11 and 12 tightened. The telescoping members are thus disposed longitudinally with relation to the board, and are substantially parallel to its working surface, as shown. If the clothes ironing operation is requiring the full length of the board, then tray 17 is pushed by

hand to a position immediately above the base side plates 18—19. In this position the tray and the flat iron are supported on the inwardly turned upper ends 43 and 44 of these side plates, and the members 16, 15 and 14 are completely telescoped inside the slideway 13. If it is desired to rest the flat iron near the middle of the board to make it more easily available to the operator, it is only necessary to grasp the handle of the flat iron and pull it in the desired direction. The flanges on tray 17 prevent the iron from sliding off the tray, and transmit the pull on the iron to the telescoping members. As soon as the tray moves off the upper ends of the base side plates 18 and 19 the runners 40 and 41 contact the ironing board surface and support the tray and its load. The length of the telescoping members and their respective slots will, of course, determine the maximum distance the tray can be moved toward the opposite end of the board. It will be understood, of course, that if the telescoping members have sufficient rigidity they would be capable of supporting the tray and its load without need for the tray resting on the surface of the board, especially since the telescoping members are non-rotatable with relation to each other. In other words the clamps could be secured to the base in a position to clamp the entire rest to a side of the board instead of to an end. In this case the tray would travel a path alongside the board instead of directly over it.

Having described the invention with sufficient clarity to enable those familiar with the art to construct and use it, I claim:

1. An extensible support for a flat iron rest comprising: a base; a plurality of elongated tubes slidably mounted one within the other for telescopic movement, the outermost tube being fixed on and rigidly supported by said base in a substantially horizontal position; an elongated rigid cylindrical member slidably mounted in the innermost tube, each of said tubes having a constant width longitudinal slot in its wall, each slot extending from a point near the inner end of a respective tube to a point near its outer end, and each tube also having a narrower constant width slot communicating at one end with the first mentioned slot and extending to the extreme outer end of its respective tube, all of said slots being in registry; an outwardly projecting stop member fixed on the peripheral surface of each encompassed tube near its inner end, each stop member being aligned with the slot in its respective tube, and projecting diametrically outwardly and slidably engaging in the wider slot of its respective encompassing tube to prevent relative rotation of the tubes, one within the other, each stop member projecting outwardly slightly less than the wall thickness of its encompassing tube; and a similar stop member on the inner end of said rigid cylindrical member for similar cooperation with the wider slot in the innermost tube.

2. An extensible support for a flat iron rest comprising: a base; a plurality of elongated tubes slidably mounted one within the other for telescopic movement, the outermost tube being fixed on and rigidly supported by said base in a substantially horizontal position; an elongated rigid cylindrical member slidably mounted in the innermost tube, each of said tubes having a constant width longitudinal slot in its wall, each slot extending from a point near the inner end of a respective tube to a point near its outer end, and

each tube also having a narrower constant width slot communicating at one end with the first mentioned slot and extending to the extreme outer end of its respective tube, all of said slots being in registry; an outwardly projecting stop member fixed on the peripheral surface of each encompassed tube near its inner end, each stop member being aligned with the slot in its respective tube, and projecting diametrically outwardly and slidably engaging in the wider slot of its respective encompassing tube to prevent relative rotation of the tubes, one within the other, each stop member projecting outwardly slightly less than the wall thickness of its encompassing tube; a similar stop member on the inner end of said rigid cylindrical member for similar cooperation with the wider slot in the innermost tube; and an elongated longitudinally disposed diametrically outwardly projecting rib carried peripherally on said rigid cylindrical member, the circumferential width of said rib being such as to permit it to enter and slidably engage in each of the narrower slots in the respective tubes, the diametric thickness of said rib being substantially equal to the combined wall thickness of all of said tubes.

3. An extensible flat iron rest for ironing boards comprising: a base; a plurality of elongated tubes slidably mounted one within the other for telescopic movement, the outermost tube being fixed on and rigidly supported by said base in a substantially horizontal position; an elongated rigid cylindrical member slidably mounted in the innermost tube, each of said tubes having a constant width longitudinal slot in its wall, each slot extending from a point near the inner end of a respective tube to a point near its outer end, and each tube also having a narrower constant width slot communicating at one end with the first mentioned slot and extending to the extreme outer end of its respective tube, all of said slots being in registry; an outwardly projecting stop member fixed on the peripheral surface of each encompassed tube near its inner end, each stop member being aligned with the slot in its respective tube, and projecting diametrically outwardly and slidably engaging in the wider slot of its respective encompassing tube to prevent relative rotation of the tubes, one within the other, each stop member projecting outwardly slightly less than the wall thickness of its encompassing tube; a similar stop member on the inner end of said rigid cylindrical member for similar cooperation with the wider slot in the innermost tube; clamping means for securing said base to an ironing board with the outermost tube at a level above the ironing board surface; and a flat iron supporting tray rigidly secured on the outer end of said rigid cylindrical member.

4. The flat iron rest described in claim 3, and skids affixed to the under side of said tray for contacting and sliding along the ironing board surface during extension and retraction of said tubes.

CORA A. STEEN.
